CLAIM

The ornamental design for the adjustable-head electronic flash unit, as shown and described.

DESCRIPTION

FIG. 1 is a front elevational view of an adjustable-head electronic flash unit showing my new design;
FIG. 2 is a rear elevational view thereof;
FIG. 3 is a top plan view thereof;
FIG. 4 is a bottom plan view thereof;
FIG. 5 is a left side elevational view thereof;
FIG. 6 is a right side elevational view thereof;
FIG. 7 is a front perspective view thereof;
FIG. 8 is a front perspective view thereof, with the light emitting element shown in an alternate position.

FIG. 1

FIG. 2

FIG. 5

FIG. 6

FIG. 3

FIG. 4

FIG. 7

FIG. 8
